UNITED STATES PATENT OFFICE

JOSEPH M. DU BOIS, OF BELLAIRE, OHIO

DESIGN FOR A HANDLED TRAY OR SIMILAR ARTICLE

Application filed April 6, 1931. Serial No. 39,381. Term of patent 3½ years.

To all whom it may concern:

Be it known that I, JOSEPH M. DU BOIS, a citizen of the United States of America, and resident of Bellaire, county of Belmont, and State of Ohio, have invented a new, original, and ornamental Design for a Handled Tray or Similar Article, of which the following is a specification, reference being had to the accompanying drawings, in which—

or similar article, showing my new design; Figure 2 is a side elevation of the same; and—

Figure 3 is a sectional elevation on line 3—3, Fig. 1.

I claim:

The ornamental design for a handled tray or similar article, as shown.

JOSEPH M. DU BOIS.
